UNITED STATES PATENT OFFICE.

WILLIAM HENRY MORGAN, OF ALLIANCE, OHIO, ASSIGNOR OF THREE-FOURTHS TO THOMAS R. MORGAN, SR., THOMAS R. MORGAN, JR., AND JOHN R. MORGAN, OF SAME PLACE.

GRAVITY-BRAKE FOR VEHICLES.

SPECIFICATION forming part of Letters Patent No. 496,429, dated May 2, 1893.

Application filed November 25, 1891. Serial No. 413,049. (No model.)

To all whom it may concern:

Be it known that I, WILLIAM HENRY MORGAN, of Alliance, in the county of Stark and State of Ohio, have invented certain new and useful Improvements in Gravity-Brakes for Vehicles; and I do hereby declare the following to be a full, clear, and exact description of the invention, such as will enable others skilled in the art to which it appertains to make and use the same.

My invention relates to an improvement in gravity brakes designed for electrically propelled machines and more particularly for electrically propelled overhead traveling cranes. The overhead traveling cranes actuated by an angular shaft located close to and parallel with one of the track rails on which the crane traveled are slow in their movements when compared with the electric crane, and never attained such a speed that the momentum carried it any appreciable distance after the power transmitting devices were thrown out of action. With the electric crane considerable speed is attained and after the current is cut off from the motor the momentum attained is sufficient to drive the crane a considerable distance.

The object of this invention is to provide a brake that will be automatically brought into operation the instant the current is broken, and it consists in the parts and combination of parts as will be more fully described and pointed out in the claims.

In the accompanying drawings, Figure 1 is a view in transverse section of an overhead traveling crane. Fig. 2 is a plan view of one end of same. Fig. 3 is a diagrammatic view showing the brake in the motor circuit and Fig. 4 is an enlarged view in elevation of the brake.

These cranes ordinarily are composed of two heavy girders A resting at their ends on cradles B, the latter having wheels C, C' adapted to run on elevated rails D. The bridge or crane is also provided with tracks E secured to the girders A and running lengthwise the bridge and from one cradle B at one end of the bridge to the cradle on the opposite end. The tracks E are for the trolley (not shown) which latter carries the hoisting mechanism

and is adapted to move from one end of the bridge to the other.

Secured to the bridge near one end thereof, is the electric motor F which latter is geared by the mechanism to be now described to the driving wheels C' of the crane for propelling same. The motor F is provided on its armature shaft, with the pinion a which latter meshes with the larger pinion b fast on one end of the shaft c. This shaft c carries at its opposite end a small pinion d which meshes with the larger pinion e fast on the driving shaft G. The shaft G extends lengthwise the bridge and is provided at its ends (one end only being shown) with pinions f meshing with the larger pinions f' fast to the driving wheels C'. From the foregoing it will be seen that when the armature of the motor is revolving, the bridge is in motion, and the momentum acquired is sufficient to keep the bridge moving some time after the current has been broken. To bring the bridge to a stop simultaneously with the breaking of the circuit I have provided a gravity brake adapted to be held out of operation when the motor F is in operation, by an electro magnet included in the motor circuit and energized by the current flowing therethrough. This brake consists of a flexible strap h secured at one end to a bracket or other fixed support i, and passing under and partly embracing the brake wheel H rigidly fastened to the armature shaft of the motor; the other end of the strap is secured to a short arm h' of lever I pivoted to the motor frame. On the outer ends of the pole pieces of the motor F there is secured an electric magnet consisting of two solenoids J yoked together and provided with movable cores l joined by an armature J' which moves with said cores. The lever I has its long arm jointed to the center of the armature by means of a sliding pivotal connection. The solenoids are included in the circuit of the motor F, so that when the motor is in operation, the current or part of same passes through the solenoids, and energizing them, causes them to draw up the armature thereby moving the lever I on its pivot and moving the brake strap away from the brake wheel H and offer no resistance to the

free rotation of the latter. When the circuit through the motor is broken either accidentally or purposely the solenoids will be de-energized and allow the armature to drop away 5 from them by its own weight, moving the lever I with it. This movement of the lever elevates the short arm h thereof and forces the strap into engagement with the brake wheels. The weight of the cores, armatures 10 and long arm of the lever, is sufficient to apply the brake strap to the brake wheel with a force sufficient to securely hold the said brake wheel against rotation, and as the brake wheel is thus locked, it follows that the driving shaft 15 G is also locked, and hence by the time the armature comes to a rest the crane is also brought to rest by the automatic brake.

I have described this brake in connection with a traveling crane, but it could be applied 20 to other vehicles, such for instance as electric cars, and hence I would have it understood that I do not confine the application of my device to traveling cranes, nor do I confine myself to the exact details of construction 25 shown and described, but consider myself at liberty to employ the brakes in connection with any vehicle or movable device, and to make such changes and alterations therein, as fairly fall within the spirit and scope of 30 my invention.

Having fully described my invention, what I claim as new, and desire to secure by Letters Patent, is—

1. The combination, with a truck or frame 35 mounted on wheels, an electric motor for propelling same and a brake wheel of a gravity brake consisting essentially of a pivoted lever connected at its short arm to a suitable

friction device and carrying an armature on its long arm, and an electro magnet located 40 above the armature and in the motor circuit and adapted to act on the armature to hold the brake out of contact with the brake wheel, substantially as set forth.

2. In a gravity brake the combination with 45 an electric motor and a brake wheel, of a gravity brake consisting essentially of a pivoted lever connected at its short arm to a suitable friction device and carrying an armature on its long arm, and an electro magnet located 50 above the armature, the said electro magnet being in the motor circuit and adapted to act on the armature to hold the brake out of contact with the brake wheel when the motor circuit is closed, substantially as set forth. 55

3. The combination with a truck or frame mounted on wheels, an electric motor for propelling same, and a brake wheel on the armature shaft, of a gravity brake consisting of a flexible strap secured at one end and partly 60 embracing the brake wheel, a pivoted lever the short arm of which is secured to said strap, and an armature secured to the long arm of said lever and an electric magnet above the armature and in the motor circuit 65 acting on the armature to hold the strap out of contact with the brake wheel when the motor circuit is closed, substantially as set forth.

In testimony whereof I have signed this specification in the presence of two subscribing witnesses.

WILLIAM HENRY MORGAN.
